TOY CROSSBOW

Paul W. White, New Haven, Conn., assignor to Parva Products Company, Chicago, Ill., a corporation of Delaware

Application October 15, 1947, Serial No. 141,925

Term of patent 7 years

(Cl. D34—15)

To all whom it may concern:

Be it known that I, Paul W. White, a citizen of the United States, residing at New Haven, in the county of New Haven and State of Connecticut, have invented a new, original, and ornamental Design for Toy Crossbow, of which the following is a specification, reference being had to the accompanying drawing, forming a part thereof.

Fig. 1 is a side elevational view of a toy crossbow embodying my new design;

Fig. 2 is a top plan view of the toy crossbow shown in Fig. 1; and

Fig. 3 is a front elevational view thereof.

The opposite side of the toy crossbow is substantially the same as the side shown in Fig. 1.

The dotted line showing of a projectile is for illustrative purposes only.

I claim:

The ornamental design for a toy crossbow, substantially as shown and described.

PAUL W. WHITE.
